METHOD OF AND APPARATUS FOR FORMING CABLES

Application filed November 30, 1926. Serial No. 151,855.

This invention relates to methods of and apparatus for forming cables, and more particularly to methods of and apparatus for forming flat and oval types of stranded cable.

In some instances, particularly in connection with interconnecting of electrical circuits in telephone switchboards, it is desirable to employ cables composed of insulated electrical conductors and accurately formed into oval or substantially flat cross sections, to agree with the size and compact arrangement of the associated apparatus.

The primary objects of this invention are to provide a simple and effective method of and apparatus for expeditiously and accurately stranding a cable into a desirable size and shape.

In order to obtain these and other objects and in accordance with the general features of the invention, one embodiment of the invention in an apparatus by means of which the method may be efficiently practiced includes a pair of parallel rollers adapted to 25 form twisted strands into a cable having a substantially flat or oval cross section. These rollers are adapted to be adjusted angularly with respect to a second pair of rollers arranged in tandem therewith for 30 compressing strands of material to form them into a cable having a substantially flat cross section. By adjusting the first mentioned forming rollers angularly with respect to the axes of the second pair of 35 rollers in a direction which is reverse to the twist which has been imparted to the strands, the tension of certain of the strand portions extending between the two pairs of rollers is relieved and upon passing 40 through the second pair of rollers, a flattened or oval type of cable is formed which is very compact in structure and which conforms to a desired form of cross section.

These and other objects will be apparent 45 from the following detailed description and the accompanying drawings, wherein

Fig. 1 is an elevational view of a forming mechanism which is adapted for application to conventional types of cable forming 50 machines;

Fig. 2 is an end elevational view of the device shown in Fig. 1;

Fig. 3 is a transverse sectional view taken on the line 3—3 of Fig. 1;

Fig. 4 is a diagrammatic representation 55 of a material twisting and serving mechanism and cable forming rollers associated therewith;

Figs. 5, 6, and 7 are transverse sectional 60 views of the stranded cable disclosing relative positions of the individual strands as they are progressively associated with the forming mechanism, these sections being taken on lines 5—5, 6—6, and 7—7, respectively, of Fig. 4.

Referring now to the drawings wherein like numerals have been employed to designate similar parts throughout the various figures, it will be observed that a forming mechanism 10 is disclosed in Fig. 1 which is 70 provided with a shank 11 capable of application to the stationary support (not shown) of a conventional cable serving head 12 (Fig. 4). This shank is formed with a bifurcated head 14 comprising a pair of branches 75 15 (Figs. 1 and 3). Positioned between these branches 15 and rotatable on pins or bolt members 16 are a pair of spaced forming rollers 18.

A pair of spaced forming rollers 19 are 80 mounted upon pins or bolts 21 which extend between a pair of bracket members 22. These brackets 22 are carried by a circular plate or disc 24 having a central opening 25, said disc being adapted for association with 85 the branches 15 as clearly shown in Fig. 1. The plate 24 is provided with a circular raised portion 27 which fits within a companion recess 28 (Fig. 3) formed in the branches 15 and by this construction the 90 plate 24 is retained coaxially with respect to the axis of rotation of the head 14. Brackets 30 secured at opposite ends of the branches 15 are provided with openings to receive clamping bolts 31 which extend 95 through arcuate slots 32 formed in the plate 24 and it will be clear from this construction that upon the loosening of a pair of tightening nuts 33 threaded upon the bolts 31, the plate 24 and consequently the roll- 100

ers 19 carried thereby may be adjusted angularly with respect to the rollers 18 within the head 14.

In Fig. 4 a diagrammatic representation 5 of a conventional strand forming and twisting head 34 is disclosed and to more clearly disclose the functional characteristics of the rollers 18 and 19, said rollers have been diagrammatically shown disassociated from 10 their supporting structures. It is common practice, in some instances, to draw strands 35, such as insulated electrical conductors, by means of a capstan 37 or any other suitable mechanism through the twisting head 15 34 during the rotation thereof and through a forming die normally positioned at the 20 position occupied by the rollers 19 in Fig. 4 and then through a serving mech- 25 anism 38.

In use, the forming mechanism 10 is fixed 30 in position upon the stationary support (not shown) of the serving head 12 and strands 35 are drawn between the rollers 18 and 19 after the rollers 19 have been angularly adjusted with respect to the rollers 18 35 as shown in Figs. 1 and 4. It is to be understood that the axes of the rollers 19 are angularly adjusted with respect to the axes of 40 the rollers 18 in a direction which is reverse to that of the stranding twist imparted by the rotation of the head 34, or conversely, that the resulting angular relation of the rollers 18 with respect to the rollers 19 is in 45 a direction similar to that of the stranding twist. The direction of rotation of the twisting head 34 is indicated by the arrows in Figs. 4 and 5. Immediately prior to the introduction of the strands 35 between the 50 rollers 19, the strands will assume a spaced relation substantially as shown in Fig. 5 and immediately subsequent to the compression and passage of the strands between these 55 rollers, they will assume a cross sectional form substantially as shown in Fig. 6. By reason of the particular angular relation between the axes of the rollers 18 and 19 disclosed, it will be understood that more strand will be paid out from the twisting 60 head 34 than if the rollers were parallel and that the tension in some of the strands at the outer edges as indicated by the numeral 40 (Fig. 6) will be relieved. This 65 relieving effect is similar to that experienced by the outermost strands of a rope or cable when, one portion thereof is held in a fixed 70 position and another portion in proximity thereto is gripped and turned in a direction which tends to remove the twist in the 75 rope or cable. This momentary relief in the tension of certain of the strands enables the rollers 18 to compress or act upon the composite group of strands so as to form them into a very compact group having a cross 80 section as shown in Fig. 7 which is uniform

in compactness and properly shaped. By employing the method which may be readily practiced by means of the disclosed apparatus, it has been found that any tendency of the individual strands to become distorted is eliminated and hence when the cable is brought into association with a tapping or serving mechanism, the cross section thereof conforms to the desired flattened form. The relative lengths of the major 70 and minor cross sectional dimensions of the finished cable may be controlled within specified limits by the angular adjustment of the pair of rollers. It has also been found that by the practice of this method flat and oval types of cables may be produced which are not only more uniform in cross sectional characteristics but which are thinner and wider than those capable of being produced by the practice of methods now in 75 common use.

It is to be understood that the invention is not limited to the exact construction and operation of the apparatus herein described and that the appended claims have been 80 drawn to define modifications which come within the true spirit and scope of the invention.

What is claimed is:

1. In an apparatus for forming stranded cables, means for twisting a plurality of strands, means for drawing the strands through the twisting means, means for forming the twisted strands drawn therethrough, and a second forming means disposed at an acute angle with respect to the first mentioned forming means in a direction similar to the direction of twist imparted to the strands and in tandem to the first forming means. 100

2. In an apparatus for forming stranded cables, means for twisting a plurality of strands, means for drawing the strands through the twisting means, a pair of rollers for forming the twisted strands, and a second pair of forming rollers arranged in tandem therewith, said pairs of rollers being angularly adjustable with respect to each other. 110

3. In an apparatus for forming stranded cables, means for twisting a plurality of strands, means for drawing the strands through the twisting means, a pair of rollers for forming the twisted strands, and a second pair of forming rollers disposed at an acute angle with respect to the first pair of rollers in a direction similar to the direction of twist imparted to the strands and in tandem to the first forming rollers. 115

4. In an apparatus for forming stranded cables from a plurality of strands, means for advancing the strands, means for twisting the strands, a roller for partially forming the twisted strands, a second roller disposed at an angle to the first roller for completing the formation of the twisted 120 125 130

strands into a cable of a predetermined cross section, and means for adjusting the angular relation of the rollers with respect to each other to form a cable of a different cross section.

5. In an apparatus for forming stranded cables from a plurality of strands, means for advancing the strands, means for twisting the strands, a pair of spaced rollers interposed between the advancing means and the twisting means for compressing the twisted strands into a composite cable of a predetermined cross section, a second pair of spaced rollers interposed between the twisting means and the first pair of rollers and disposed with their axes at an angle to the axes of the first rollers for consolidating the strands into a flat cable.

6. A method of forming a flat cable from a plurality of strands, comprising advancing the strands in spaced lateral relation to each other, causing the advancing strands to converge into a flat formation by exerting a lateral pressure thereagainst while twisting the strands about each other, and consolidating said formation by exerting a lateral pressure thereagainst at a point longitudinally removed along the cable from the point of convergence and disposed at an angle to the first mentioned lateral pressure.

7. A method of forming a flat cable from a plurality of strands, comprising advancing the strands in spaced lateral relation to each other, converging the strands into a flat formation by exerting opposite lateral pressures against the strands while imparting a twist to said formation, and consolidating said formation by exerting opposite lateral pressures thereagainst at an angle to the first mentioned lateral pressures and at a point longitudinally removed along the cable from the first lateral pressures exerted.

8. An apparatus for forming flat cable from a plurality of strands, comprising means for advancing the strands in spaced lateral relation to each other, means for twisting the strands about each other during such advancement, means for exerting lateral pressure against the twisted strands to cause them to converge into a flat formation, and means disposed forwardly of the first mentioned means for exerting a lateral pressure at an angle to the first mentioned lateral pressure to consolidate said formation into a cable.

9. An apparatus for forming flat cable from a plurality of strands, comprising a twisting head, means for advancing the strands through the twisting head, a pair of cooperating surfaces disposed between the twisting head and the advancing means and adapted to exert a lateral pressure against the strands to cause them to converge into a flat formation, and a second pair of co-

operating surfaces disposed at an angle to the first mentioned surfaces removed longitudinally along the cable from the first pair of cooperating surfaces and adapted to consolidate said formation into a flat cable.

10. An apparatus for forming flat cable from a plurality of strands, comprising a rotating head for twisting the strands about each other, a pair of cooperating surfaces disposed forwardly of the rotating head and adapted to cause the strands to converge into a flat formation without arresting the twisting thereof, a second pair of cooperating surfaces disposed forwardly of and at an angle to the first mentioned surfaces and adapted to consolidate said formation into a flat cable, and means for advancing the strands through the rotating head and the cooperating surfaces.

In witness whereof, we hereunto subscribe our names this 16th day of November A. D., 1926.
